UNITED STATES PATENT OFFICE.

MEREDITH LEITCH, OF POUGHKEEPSIE, NEW YORK, ASSIGNOR TO THE DE LAVAL SEPARATOR COMPANY, A CORPORATION OF NEW JERSEY.

RING-INSERTER FOR MILKING-MACHINE TEAT-CUPS.

1,363,522.

Specification of Letters Patent. Patented Dec. 28, 1920.

Application filed April 2, 1919. Serial No. 286,973.

To all whom it may concern:

Be it known that I, MEREDITH LEITCH, a citizen of the United States, residing at Poughkeepsie, county of Dutchess, and 5 State of New York, have invented a new and useful Improvement in Ring-Inserters for Milking-Machine Teat-Cups, of which the following is a full, clear, and exact description, reference being had to the accompanying drawings, which form a part 10 of this specification.

The object of my invention is to provide means for inserting expanding rings into elastic tubes. The invention, while applicable to other analogous uses, is particularly adapted for the insertion of the metallic ring that is used to expand a part of the flexible liner in certain types of teat cups for milking machines.

20 In the drawings, which show a ring inserter embodying my invention in a preferred form:

Figure 1 is a plan view of one member of the ring inserter.

25 Fig. 2 is a side view of the same member.

Fig. 3 is a side view of the other member.

30 Fig. 4 is a side view of both members of the inserter, in connection with a flexible tube (in cross-section), showing the parts in the positions they assume during the first step of the process of inserting a ring into the tube.

Fig. 5 is a view, similar to Fig. 4, showing 35 the relation of the parts during the second step.

Fig. 6 is a view, similar to Figs. 4 and 5, showing the relation of parts during the third step.

40 Fig. 7 shows a tube with the ring in place.

a is a plate having several elastic fingers *b* upstanding therefrom in a frusto-conical relation. *c* is a base for a pedestal having a portion *d* longer than the fingers *b* and of a diameter greater than the inside diameter and less than the outside diameter of the ring to be inserted and above that a short portion *e* having a diameter slightly 45 less than the inside diameter of the ring. *f* is one of the rings to be inserted and *g* a rubber tube.

In operating the device to insert the ring

into the tube, one of the rings *f* is placed around the small part *e* of the pedestal 55 and rests on the shoulder at the top of the large portion *d*. The fingers *b* are then squeezed together at the top and one of the rubber tubes is slipped a short distance over them. The plate *a* and fingers *b* are 60 then forced down around the ring *f* supported on the shoulder of the pedestal and carry the tube down to the position shown in Fig. 5. The upper ends of the fingers are now below the ring *f*. The plate and 65 fingers are then lifted off the pedestal, pushing the ring *f* ahead of them, until the free ends of the fingers spring into their normal position, as shown in Fig. 6. The plate and fingers are then removed, leaving 70 the tube with the ring in place, as shown in Fig. 7.

Having now fully described my invention, what I claim and desire to protect by Letters Patent is:

1. A device for inserting a ring into an elastic tube, comprising, in combination, means to stretch the tube and means to pass the ring through the stretching means into the tube.

2. A device for inserting a ring into an elastic tube comprising an expansible tube-stretching member adapted to be inserted into the mouth of the tube and a ring-inserting member to carry the ring toward and 85 into the mouth of the tube and during such movement to expand the expansible member and thereby allow the entry of the ring.

3. A device for inserting a ring into an elastic tube comprising a member, normally 90 contracted, but adapted to be expanded to open the mouth of the tube to receive the ring, and a member adapted to expand the expansible member and insert the ring through the expansible member into the 95 tube.

4. A device for inserting a ring into an elastic tube comprising a ring supporting and ring inserting member, and a tube-stretching member adapted to be inserted 100 into the end of the tube and to be moved, with the tube, telescopically relatively to the first member and in such movement to be expanded to permit the entrance of the ring within the tube.

5. A device for inserting a ring into an

75

90

95

105

elastic tube comprising a ring inserting member, and a member movable longitudinally relative to the ring-inserting member and adapted, in its movement, to stretch the tube and permit the entrance of the ring.

6. A device for inserting a ring into an elastic tube comprising a ring inserting member, and a member movable longitudinally relative to the ring inserting member and adapted, in its movement in one direction, to stretch the tube and permit the entrance of the ring and in its movement in the opposite direction to retract the ring with the tube in which it is inserted from the ring inserting member.

7. A device for inserting rings into elastic tubes comprising, in combination, a member having several elastic fingers adapted to be surrounded by one end of an elastic tube and a member adapted to force a ring through between the fingers so as to separate them and expand the surrounding tube and admit the ring.

8. A device for inserting rings into elastic tubes, comprising, in combination, a member having several flexible fingers in frusto-conical relation adapted to have the small end of the cone frustum surrounded by an elastic tube, and a member adapted to force a ring from the large end of the cone toward the small end, thereby separating the flex-

ible fingers and stretching the elastic tube to admit the ring.

9. A device for inserting a ring into an elastic tube comprising, in combination, a plate carrying flexible fingers in frusto-conical relation adapted to be surrounded at the small end by the tube, and a pedestal having a shoulder adapted to receive the ring and force it through the cone, thereby separating the fingers and stretching the tube to receive the ring.

10. A device for inserting a ring into an elastic tube comprising a member having an end of reduced diameter over which the ring is adapted to slip, said reduced end forming a shoulder against which said ring is adapted to rest and beyond the circumferential edge of which said ring is adapted to extend, and a series of elastic fingers normally assuming a frusto-conical relation, the approximating ends of the fingers being adapted for insertion into the tube, the fingers being adapted to be moved telescopically along the first member, thereby expanding them and the tube until the tube-engaging ends of the fingers override the ring.

In testimony of which invention, I have hereunto set my hand, at Poughkeepsie, N. Y. on this 24 day of March, 1919.

MEREDITH LEITCH.
